UNITED STATES PATENT OFFICE.

FREDERICK A. FISCHRUPP, OF WHITING, INDIANA.

DESIGN FOR AN ELECTRIC-LANTERN BASE.

46,051.

Specification for Design.

Patented July 7, 1914.

Application filed April 20, 1914. Serial No. 833,311. Term of patent 7 years.

To all whom it may concern:

Be it known that I, FREDERICK A. FISCHRUPP, a citizen of the United States, residing at Whiting, in the county of Lake and State of Indiana, have invented a new, original, and ornamental Design for Electric-Lantern Bases, of which the following is a specification, reference being had to the accompanying drawing, forming part thereof.

The figure shown in this drawing is a

view of an electric lantern base showing my new design.

I claim:

The ornamental design for an electric lantern base, as shown.

FREDERICK A. FISCHRUPP.
